DESIGN FOR A WALKING ANIMAL FIGURE

Roy A. Kropp, River Forest, Ill.

Application May 11, 1946, Serial No. 129,634

Term of patent 14 years

(Cl. D34—15)

To all whom it may concern:

Be it known that I, Roy A. Kropp, a citizen of the United States, residing at River Forest, in the county of Cook and State of Illinois, have invented a new, original, and ornamental Design for a Walking Animal Figure, of which the following is a specification, reference being had to the accompanying drawing, forming part thereof.

In the drawing:

Fig. 1 is a front view of a walking animal figure showing my new design;

Fig. 2 is a side view of the walking animal figure;

Fig. 3 is a view from the other side thereof;

Fig. 4 is a front view of the walking animal figure in another position.

I claim:

The ornamental design for a walking animal figure, as shown.

ROY A. KROPP.
